SNAP-OPEN MAGNETIC TAPE CARTRIDGE

Gary L. Allison and Vladimir Nejezchleb, Boulder,
Helfried O. Rinkleib, Longmont, and Gary L. Switser,
Boulder, Colo., assignors to International Business
Machines Corporation, Armonk, N.Y.

Filed Feb. 9, 1971, Ser. No. 114,104

Term of patent 7 years

Int. Cl. D14—02, 99
U.S. Cl. D26—14 B

FIG. 1

FIG. 2

FIG. 3

FIG. 4

FIG. 5

FIG. 6

FIG. 7

FIG. 8

FIG. 1 is a top front right side perspective view of a snap-open magnetic tape cartridge showing our new design;

FIG. 2 is a bottom rear left side perspective view thereof;

FIG. 3 is a left side elevational view thereof;

FIG. 4 is a right side elevational view thereof;

FIG. 5 is a front elevational view thereof;

FIG. 6 is a top plan view thereof;

FIG. 7 is a rear elevational view thereof; and

FIG. 8 is a bottom plan view thereof.

We claim:

The ornamental design for a snap-open magnetic tape cartridge, substantially as shown and described.
